Attorney.

UNITED STATES PATENT OFFICE.

JOHN W. HAYS, OF ERIE, PENNSYLVANIA.

STEAM-CYLINDER LUBRICATOR.

SPECIFICATION forming part of Letters Patent No. 268,667, dated December 5, 1882.

Application filed October 24, 1882. (No model.)

To all whom it may concern:

Be it known that I, JOHN W. HAYS, a citizen of the United States, residing at Erie, in the county of Erie and State of Pennsylvania, have invented certain new and useful Improvements in Steam-Cylinder Lubricators; and I do declare the following to be a full, clear, and exact description of the invention, such as will enable others skilled in the art to which it appertains to make and use the same, reference being had to the accompanying drawings, and to the letters and figures of reference marked thereon, which form a part of this specification—

15 Figure 1 being a central longitudinal vertical section of a steam-cylinder lubricator constructed with my improvements; Fig. 2, a view of a tappet for operating the lubricator, and represented as attached to the connecting-rod 20 of the steam-engine.

My invention consists in an improved device by which some moving part of the engine acts directly on the plunger which feeds the oil to the interior of the cylinder, and in connection therewith the means by which the length of the stroke of the plunger is varied at will, while the part of the engine which moves the plunger remains constant in position.

Let A represent the lubricating-pump, of any 30 suitable or ordinary construction, and B the plunger. To the pump-barrel is attached a holder, C, containing a (preferably coiled) spring, D. The pump and holder are mounted upon the cylinder of the engine or other convenient support. The outer end of the plunger is attached 35 to a sliding bolt, E, which is mounted in and reciprocates in the holder C, and projects beyond it, substantially as shown. An arm or tappet, G, is attached to the connecting-rod 40 H of the engine or equivalent moving part

thereof, so as to be in right position to strike the bolt E or extension of the plunger. The tappet G thus gives motion to the plunger in one direction, and the spring D is intended to give the reverse or return motion thereto. 45 For this purpose the spring is arranged to bear and press outward against the bolt E or an enlargement, a, on the plunger or bolt, as shown, or otherwise. The other end of the spring bears against a follower or head, I, 50 which screws into the holder C, more or less, and thus regulates the force of the spring as required. The plunger works through a packing-head, b, to confine the oil in the pump at that end. The length of the stroke of the piston, and consequently the amount of oil pumped into the cylinder, is regulated by means of a cap, K, screwed upon the outer end of the bolt E, more or less, as required. 55

This invention is very cheap and simple in construction, and its action direct and effectual.

What I claim as new, and desire to secure by Letters Patent, is—

1. The combination of the lubricator plunger-extension E, tappet G, on a movable part of the engine, and the counter-spring D, substantially as and for the purpose herein specified. 65

2. In combination with the plunger-extension E and tappet G, the cap K, adjustable upon the said plunger-extension, substantially as and for the purpose herein specified. 70

In testimony whereof I affix my signature in presence of two witnesses.

JOHN W. HAYS.
